UNITED STATES PATENT OFFICE.

JOHN H. MOCK, OF JETMORE, KANSAS.

DITCHING MACHINE.

1,111,398.

Specification of Letters Patent. Patented Sept. 22, 1914.

Application filed September 2, 1913. Serial No. 787,739.

To all whom it may concern:

Be it known that I, JOHN H. MOCK, a citizen of the United States, residing at Jetmore, in the county of Hodgeman and State of Kansas, have invented certain new and useful Improvements in Ditching-Machines; and I do hereby declare the following to be a full, clear, and exact description of the invention, such as will enable others skilled in the art to which it appertains to make and use the same.

This invention relates to ditching machines and one of the principal objects thereof is to provide a ditching machine having scoops which may be adjusted to the desired depth.

A further object is to provide a ditching machine whereby the dirt may be thrown to either side of the ditch at the will of the operator.

A further object of my invention is to provide a ditching machine which will be simple, durable, and efficient in operation and inexpensive to manufacture.

With these and other objects in view the invention consists in the construction, combination and arrangement of parts herein-after more fully described, and claimed, and illustrated in the accompanying drawings, in which like characters of reference indicate like parts throughout the several views and in which,

Figure 1 is a vertical longitudinal sectional view through the machine, showing the scoops and elevator in side elevation. Fig. 2 is a top plan view of the machine, and, Fig. 3 is a vertical longitudinal view through the lower scoop and the lower end of the elevator.

In carrying out my invention I provide a substantially rectangular frame having side bars 1, a front bar 2 and a rear bar 3, an arch shaped axle 4 being pivoted on a bumper 5 secured to the front bar and carrying front wheels 6, and an axle 7 being journaled in brackets (not shown) under the rear end of the frame and carrying driving wheels 8. A tongue 9 is secured to the axle 4 above the same, and draft animals are adapted to be hitched to the tongue, the tongue being braced to the axle 4 and adapted to turn the same for guiding the machine.

A cross board 10 is positioned on the frame toward the forward end thereof and carries a driver's seat 11. Secured to the

side bars 1, forwardly of the board 10, is a metal arch 12, whose central portion comprises a block 12^a, pivoted by means of pins 12^b, to the adjacent portions of arch 12, and said block is provided with a central opening therein which is adapted to receive a vertical rack bar 13, adapted to be actuated by means of a pinion 14 secured to a stub axle 15, which extends through the opening and which is provided with a wheel 16 adapted to be operated from the driver's seat. The rack bar 13 is positioned between the pinion 14 and the end of the opening in the block 12^a. The lower end of the rack bar is bifurcated, as at 17, and a disk 18 is formed integral with the lower end of the bifurcations and is provided centrally thereof with an opening for receiving a bolt 19 which passes through a beam 20, the front end of which is provided with a clevis 21 adapted to receive a chain 22, which is hitched to the draft animals. Near the rear end of the beam 20 are secured scoops 23 and 24, each of which has a bottom and side walls, the latter being formed with arms 25 which curve inwardly and are secured as at 26 to the beam. The scoop 23 is somewhat shorter than the scoop 24 and is positioned at a slight distance above the front end of the latter and is adapted to engage the earth for cutting the same and delivering it to the scoop 24, the latter gathering the earth below the scoop 23.

An arcuate member 60 has its ends pivoted by means of removable bolts 61 to the lower ends of braced bars 62, which are secured to the frame and which are provided with a number of openings to allow adjustment of member 60, longitudinally of the bars. The central portion of member 60 is bent into a substantial U-shape, and a heavy bolt 63 passes through the arms of the U, and through the rack bar 13, pivoting said bar to the arcuate member. By this means the force of pulling the machine is exerted through member 60, and bars 62, and the rack bar is relieved of strain. It is evident that as the plows are raised or lowered, the difference in distance between rack 13 and the vertical plane of bars 62, is compensated for by the swinging of block 12^a on its pivots.

A rectangular supporting frame 27 is pivoted, as at 28, to the central portion of the axle 7 and at its upper end supports a shaft 116

29, which is provided at one end with a cog wheel 30, over which a chain 31 runs, the opposite end of the chain running over a cog wheel 32 supported by a shaft 33 which is journaled in the frame 27 above the axle 7, one end of the shaft 33 being provided with a gear wheel 34 adapted to engage a gear 35 on the axle 7, whereby rotary motion is imparted through the chain 31 to the shaft 29. A clutch 36 is provided for throwing the gear 35 into and out of engagement with the gear 34 and the said clutch is adapted to be operated from the driver's seat.

15 Pivoted on the shaft 29 are the upper ends of the side members of an elevator 37, the lower ends supporting a shaft 38, which passes through the sides of the scoop 24 and which co-acts with the shaft 29, in supporting a conveyer belt 39, which is provided with cross bars 43 for gathering the dirt from the scoop 24 and carrying the same upward on the conveyer. The rear end of the beam 20 is provided with a cross bar 41, the ends of which extend through the sides of the elevator 37 and are adapted to work in slots 42 therein, the sides of the scoop 24 being also slotted where the shaft 38 extends therethrough, so that the beam 20 may 25 swing on its pivot 19 without disturbing or twisting the elevator 37. A wall 40 connects the sides of the elevator 37 and is adapted to support the conveyer belt. The sides of the elevator 37 lie within the sides of the scoop 24 and are spaced slightly therefrom, the bottom of the scoop being formed with an upwardly inclined wall 57 at its rear end for depositing the earth onto the belt 39.

20 Pivoted on the shaft 29 on the outer sides of the elevator 37 are the sides of a chute 44, the latter being inclined downwardly and adapted to rest at its lower end against one of the sloping sides of a hopper 45, which is secured to the end bar 3 of the 25 frame of the machine, and which is provided with oppositely extending spouts 46 which have their outer ends disposed well beyond the edges of the ditch, said hopper being adapted to receive the earth carried up by 30 the conveyer for depositing the same on either or both sides of the ditch, as the operator may wish, a gate 47 being pivoted at its lower end between the meeting ends of the sides of the spouts and which is provided with a shaft 48 extending through 35 the bar 3 and having a lever arm 49 which is adapted to be actuated by means of a rod 50 connected to one arm of a bell crank lever 52, the opposite arm of which is connected by a rod 53 to the lever 54, the latter being pivoted to the segment 55 on the cross board 10, the usual dog being provided on the lever 54. It is obvious that by this construction the gate 47 may be thrown 40 either to the right or left for closing one

of the chutes, whereby the dirt will be deposited through the other chute on either side of the ditch, or the gate may be left in a vertical position so that the dirt will be equally deposited on both sides of the 70 ditch.

75 A guide wheel 56 is pivoted to the bar 20 at the front end thereof and the diameter of said wheel is equal to the width of the scoops, said guide wheel being adapted to contact with the sides of the ditch for maintaining the scoops in proper alinement, it being understood, however, that when the ditch is first started, the wheel 56 will be above the surface of the ground, in which 80 case the scoops are guided by the pull on the draw bar 20. The conveyer 37 is somewhat less in width than the width of the scoops, so that the former will not contact with the sides of the ditch and will allow 85 enough play for turning curves in the ditch, and also allowing for enough play between the sides of the scoop 24 and the sides of the elevator to allow play of the shaft 38 in the side of the scoop, as the machine goes 90 around a curve in the ditch.

95 By reason of the supporting frame 27 being pivoted on the shaft 7, the conveyer is free to be raised or lowered as the beam 20 is raised or lowered, and this action will cause the frame to rock on the shaft 7, this action not interfering with the operation of the chute because the lower end of the chute 44 rests against the hopper 45, but is not secured thereto.

100 The shaft 38 is positioned at such a distance above the bottom of the scoop 24 as to allow the passage of the cross bars 43 between said shaft and the bottom of the scoop.

105 Although I have described the preferred embodiment of my invention, I reserve and may exercise the right to make such changes in the construction, combination and arrangement of parts as do not depart from 110 the spirit of the invention or scope of the appended claims.

Having thus fully described my invention, what I claim as new and desire to secure by Letters Patent of the United 115 States is:

1. A ditching machine providing a frame, a rack bar slidably supported thereby, a beam pivoted to said rack bar, scoops carried by said beam and adapted to collect 120 the earth, a supporting frame, an elevator pivoted at one end to said frame and loosely connected at the opposite end to said beam, a shaft carried by said elevator and extending through slots in the side walls of one 125 of said scoops, means for operating said elevator for removing the earth from said scoops, and means for depositing said earth from the elevator.

2. A ditching machine including a wheel 130

supporting frame, a scoop beam, means for connecting the scoop beam to the frame whereby the beam may be adjusted, a plurality of scoops carried by said beam, an endless conveyer having its lower terminal movably connected to one of said scoops and likewise movably connected to said beam, and means supporting the upper terminal of said conveyer and coating with said mova-

ble connections whereby the angle of inclination of the conveyer may be varied.

In testimony whereof I have signed my name to this specification in the presence of two subscribing witnesses.

JOHN H. MOCK.
